CLAIM

The design of a toilet training chair for children, as shown and described.

DESCRIPTION

FIG. 1 is a right side elevational view of a toilet training chair for children showing my new design, the left side being a mirror image of the right side shown;
FIG. 2 is a top plan view thereof;
FIG. 3 is a front elevational view thereof;
FIG. 4 is a rear elevational view thereof;
FIG. 5 is a bottom plan view thereof; and
FIG. 6 is a cross-sectional view taken on line 6—6 of FIG. 5.

FIG. 1***FIG. 2******FIG. 3******FIG. 4******FIG. 5******FIG. 6***
